G. O. GILBERT.
OILER.
APPLICATION FILED DEC. 26, 1916.

Patented Sept. 25, 1917.

Inventor

GEORGE O. GILBERT

By *Watson E. Coburn*
Attorney

UNITED STATES PATENT OFFICE.

GEORGE O. GILBERT, OF MONTROSE, COLORADO.

OILER.

1,241,207.

Specification of Letters Patent. Patented Sept. 25, 1917.

Application filed December 26, 1916. Serial No. 138,914.

To all whom it may concern:

Be it known that I, GEORGE O. GILBERT, a citizen of the United States, residing at Montrose, in the county of Montrose and

5 State of Colorado, have invented certain new and useful Improvements in Oilers, of which the following is a specification, reference being had to the accompanying drawings.

10 This invention relates to certain improvements in oilers and it is an object of the invention to provide a device of this general character which, at all times, is non-leakable and which includes a reservoir that will retain oil therein without spilling or leaking when the device is in use as well as when the device is not in use.

15 The invention also has for an object to provide a novel and improved oiler including a gun adapted to be sheathed, when not in use, within a reservoir containing a supply of oil together with means whereby the gun is caused to automatically operate to charge the same before the gun is removed 25 from within the reservoir.

20 The invention consists in the details of construction and in the combination and arrangement of the several parts of my improved oiler whereby certain important advantages are attained and the device is rendered simpler, less expensive and otherwise more convenient and advantageous for use, all as will be hereinafter more fully set forth.

30 The novel features of the invention will hereinafter be definitely claimed.

35 In order that my invention may be the better understood, I will now proceed to describe the same with reference to the accompanying drawings, wherein is disclosed 40 a longitudinal sectional view taken through an oiler constructed in accordance with an embodiment of my invention.

45 As disclosed in the accompanying drawings, C denotes a cylindrical container of predetermined dimensions and having one end closed by the substantially cone-shaped head 1, the apex of which being disposed outwardly and it is also to be noted that said 50 head 1 is positioned inwardly of the adjacent end of the container so that the apex of the head 1 will be substantially flush with the adjacent end of said container C so that if desired said container may be conveniently rested upon said end.

The opposite end of the container is provided with a removable head or cap 2 which affords a convenient means for filling the container C with a supply of oil.

At substantially its axial center the removable head of cap 2 is provided with an opening 3 defined by an outstanding annular flange or sleeve 4 provided with external threads, and extending inwardly from the removable head or cap 2 and in continuation 60 of the annular flange or sleeve 4 is a tube 5. The tube 5 is of such a length as, when the removable head or cap 2 is in applied position upon the container C, to terminate in close proximity to the axial center or 65 apex of the head 1, and the inner end portion of said tube 5 is tapered, as at 6, and is provided in its inner end with the restricted opening 7.

70 G denotes an oil gun readily insertible 75 within the tube 5 through the entrance afforded by the annular flange or sleeve 4 and, as herein embodied, said gun G includes a barrel 8 provided with an elongated tapering discharge nozzle 9 at one end thereof 80 and which nozzle 9 is adapted to extend through the restricted opening 7 in the inner end of the tube 5, the periphery of said nozzle 9 preferably having frictional contact with the wall of said opening. 85

85 Mounted for rectilinear movement within the barrel 8 is the piston 10 operatively engaged with the rod 11, said rod 11 extending exteriorly of the barrel 8 through the end thereof remote from the nozzle 9. The outer 90 end portion of the rod 11 is provided with the cap 12 adapted to be engaged with the threaded periphery of the sleeve or annular flange 4, whereby it will be perceived that the gun G is effectively held within the tube 95 5 and the piston 10 maintained at the limit of its movement inwardly of the barrel 8.

95 The rod 11 is of a length less than the length of the barrel 8 so that the expansible member 14 may be readily interposed between the piston 10 and the adjacent end portion of the barrel 8, said expansible member being herein disclosed as a conventional coil spring bearing against the inner 105 face of the piston and an annular shoulder 15 afforded by the nozzle 9.

105 It will be at once self-evident that with the gun G sheathed and locked within the tube 5, the expansible member 14 will be compressed and that when the cap 12 is dis- 110

engaged from the annular flange or sleeve 4, the expansion of the member 14 will result in an outward movement of the piston 10 whereby a charge of oil will be automatically drawn within the barrel of the gun.

It is also thought to be self-evident that in arranging the gun G within the tube 5 a charge of air will be delivered within the container C when the piston 10 is forced 10 inwardly of the barrel 8 to engage the cap 12 with the annular flange or sleeve 4. The air thus forced within the container C serves to facilitate the drawing of the oil within the barrel 8 when the piston 10 is forced 15 outwardly under the influence of the expandable member 14 as hereinbefore set forth.

If preferred the annular flange or sleeve 4 may be surrounded by a gasket 16 with which the cap 12 contacts to effectively prevent 20 any possible leakage of oil and it will also be understood that if desired a gasket 17 may be interposed between the container C and the removable head or cap 2.

From the foregoing description, it is 25 thought to be obvious that an oiler constructed in accordance with my invention is of an extremely simple and comparatively inexpensive nature and is particularly well adapted for use by reason of the convenience 30 and facility with which it may be assembled, and it will also be obvious that my invention is susceptible of some change and modification without material departure from the principles and spirit thereof and 35 for this reason I do not wish to be understood as limiting myself to the precise arrangement and formation of the several parts herein shown in carrying out my invention in practice, except as hereinafter 40 claimed.

Copies of this patent may be obtained for five cents each, by addressing the "Commissioner of Patents, Washington, D. C."

I claim:

An oiler comprising, in combination, a container having one end closed and the opposite end open, a cap co-acting with the open end of the container, said cap being 45 provided with an opening defined by an outstanding annular flange, an inwardly directed tube carried by the cap and in continuation of the annular flange, the inner end of the tube being provided with a re- 50 stricted opening, an oil gun including a barrel, a piston and an operating rod for the piston, said barrel being insertible within the tube and provided with a tapering nozzle adapted to extend through the re- 55 stricted opening of the tube, said nozzle when extended through the restricted opening of the tube terminating in close proximity to but spaced from the closed end of the container, said closed end being substantially cone shaped with the apex thereof disposed outwardly, a cap carried by the outer end portion of the rod and engageable with the outstanding flange of the first named cap for holding the gun within the tube and 60 maintaining the piston of the gun at the limit of its inward movement, said rod being of a length less than the length of the barrel, the inner end portion of the barrel being provided with an inwardly directed shoulder, and an expansible member positioned 65 within the barrel intermediate the piston and the shoulder of the barrel for constantly urging said piston outwardly.

In testimony whereof I hereunto affix my 70 signature in the presence of two witnesses.

GEORGE O. GILBERT.

Witnesses:

L. F. PONTION,
H. B. DENSON.
